CRATER LAMP

George H. Bouchard, Ipswich, Mass., assignor to
 Sylvania Electric Products Inc., Salem, Mass.,
 a corporation of Massachusetts

Application January 2, 1947, Serial No. 719,852

2 Claims. (Cl. 176—122)

1

This invention relates to electric discharge lamps of the crater type, in which the light comes from the interior of a hollow cathode usually known as a crater. Such lamps are used for many purposes, but particularly as recorder lamps in photo-transmission apparatus.

An object of my invention is to provide a better light pattern from such craters by increasing the amount of light from the crater part of the cathode. I achieve this by a reentrant portion at the closed bottom of the hollow in the cathode. The hollow may, for example, be in the form of a cylinder with a reentrant cone, hemisphere, or the like projecting from its bottom.

Further objects, advantages and features of the invention will be apparent from the following specification.

The figure shows an electrode assembly having a cathode in accordance with the invention.

The cathode 1 may be of misch metal, which is a well-known cerium-containing metal, or of thorium or some other metal of high electron-emissivity. I prefer misch metal, which seems to give better life. The cathode 1 may be a cylinder 2 into which a hole 3, for example a cylindrical hole, extends from one end 4. A projection 14 such as a reentrant cone, hemisphere or the like extends upward from the closed bottom 5 of the hole 3. A cup 6 of insulating material, for example the type known as lava, may surround the hollow cylinder 2 except at its open end 4, and may extend somewhat ahead of the cylinder 2 to space the metal anode cup 7 from the cathode. The anode 7 has the opening 8 through which light from the cathode 1 may pass. The edges 9 of lava cup 6 may be partially bevelled, and a metal annular wire ring 10 may rest on the edges 9 to space the anode 7 somewhat further from the cathode 1.

A lead-in and support wire 11 extends through the bottom of insulating cup 6 and may be threaded into the bottom 12 of cathode 1. An additional lead-in wire 13 may be welded cross-wise to the wire 11 to help hold the insulating cup 6 in place. The whole unit may then be placed in an atmosphere of gas in a sealed envelope in the manner usual in the art. A gas filling of about 18 mm. measured while the device is still hot on the usual exhaust machine,

2

will be satisfactory, the gas being about 94% neon and 6% argon. The anode cup may have the lead-in and support wires 15 welded to it.

When sufficient voltage is placed between anode 5 and cathode 1 a thin glowing layer of gas is present on the interior cathode surfaces. The brightness of this glow appears to increase with the length of glow viewed, up to a saturation value, and the projection 14 in the bottom 5 of the hole 3 probably increases the thickness of this glowing layer in the viewing direction, parallel to the axis of the cylinder 2.

For convenience in the appended claims, the closed end of the hole or cavity in the electron-emitting piece is referred to as the bottom of the hole, although it may, of course, be the top if the tube is turned around. Similarly the direction from said bottom of the hole to the open end is referred to as upward.

20 The gas pressure at room temperature may be in the neighborhood of 14 mm. A pressure a few millimeters greater than the pressure of maximum light intensity is generally preferable to give increased life.

25 The surface of the projection 14 is preferably stepped or corrugated for greater brilliancy, as shown, but may be a smooth surface if desired.

I claim:

30 1. A luminous crater electrode comprising a hollow, electron-emitting metal cylinder closed at one end only, and a conical projection extending upward inside the hollow cylinder from said closed end.

35 2. The combination of claim 1, and an insulating cup in which said electrode is seated.

GEORGE H. BOUCHARD.
